EXPANSION BRACELET HAVING TWO PARALLEL ROWS OF CONNECTING LINKS

Karl E. Stiegele, Huchenfeld, near Pforzheim, Germany, assignor to Rodi & Wienerberger Aktiengesellschaft, Pforzheim, Baden, Germany

Application July 25, 1956, Serial No. 599,990

Claims priority, application Germany August 17, 1955

4 Claims. (Cl. 59—79)

The present invention relates to expansion bracelets.

More particularly, the present invention relates to an expansion bracelet of the type which may assume contracted and expanded positions and which is normally maintained in its contracted condition.

It is an object of the present invention to provide an expansion bracelet which is composed of a minimum of parts each of which may be mass-produced at low cost and which may be easily assembled to form the complete expansion bracelet.

It is another object of the present invention to provide an expansion bracelet to which individual links can easily be added or from which excess links may readily be removed so as to make it possible to obtain an expansion bracelet of any desired length.

It is yet another object of the present invention to provide an expansion bracelet which is of pleasing appearance.

With the above objects in view, the present invention mainly consists in that improvement in an expansion bracelet which includes a series of tubular links, a plurality of first and second connecting means interconnecting the links, and spring means interconnecting the links and the connecting means. The links are arranged in a single row extending lengthwise to the bracelet, with the axis of each link extending transversely to the row. The first and second connecting means are arranged in separate rows, respectively, which also extend lengthwise to the bracelet, the connecting means being so arranged that each link is connected to one adjacent link by one of the first connecting means and to the other adjacent link by one of the second connecting means with each of the connecting means extending into the two links which it connects throughout at least of the length of such links. The spring means pivotally secure each of the connecting means to the two links which it interconnects, the links, the connecting means and the spring means being so constructed and arranged that the bracelet is capable of assuming contracted and expanded conditions and that the spring means constantly urge the bracelet into its contracted condition. Moreover, the arrangement of the parts is preferably such that the bracelet in its expanded condition assumes a zig-zag configuration.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a sectional plan view of one embodiment of the present invention taken along line 1—1 of Fig. 2;

Fig. 2 is a side elevational view of the embodiment illustrated in Fig. 1, the bracelet shown in its contracted condition;

Fig. 3 is a side view of the same embodiment, the bracelet being shown in its expanded condition;

2

Fig. 4 is a side view of a link and spring assembly of a modified embodiment of the present invention;

Fig. 5 is a plan view of the spring incorporated in the assembly shown in Fig. 4;

Fig. 6 is a side view of the spring shown in Fig. 5 as seen in the direction of the arrow 6;

Fig. 7 is an end view of the spring shown in Fig. 5 as seen in the direction of the arrow 7;

Fig. 8 is a sectional plan view of another embodiment of the present invention;

Fig. 9 is a plan view of the spring incorporated in the embodiment shown in Fig. 8;

Fig. 10 is a plan view of another embodiment of a spring according to the present invention;

Fig. 11 is a side view of the spring shown in Fig. 10 as seen in the direction of the arrow 11; and

Fig. 12 is an end view of the spring shown in Fig. 10 as seen in the direction of the arrow 12.

Referring now to the drawings and to Figs. 1—3 thereof in particular, there is shown a portion of an expansion bracelet which includes a series of tubular links 2. The same may have any desired cross-sectional configuration, and in the instant embodiment the cross-section is shown as being elongated and substantially rectangular. Each link has a pair of opposite side walls 3, an upper wall 15 and a lower wall 16. The links are in stacked relation with the side walls 3 which form the longer sides of the substantially rectangular cross-sectional configuration being transverse to the length of the bracelet and with the axis of each link extending transversely to this length. Thus, the links are aligned in a single row, and the upper walls 15 of the links together form the outer face of the bracelet, indicated generally at 15a, whereas the lower walls 16 of the links together form the engaging face, indicated generally at 16a, which is contact with the wearer of the bracelet. The surfaces are bounded by, and in the illustrated embodiment lie in planes substantially parallel to a plane common to the axes of the individual links.

The links are interconnected by a plurality of first and second connecting means 4a and 4b each of which is in the form of a substantially U-shaped member having a base and a pair of legs 6. The members 4a and 4b are arranged in two separate rows, respectively, which also extend lengthwise of the bracelet and which are near the engaging and outer surfaces of the bracelet.

In the illustrated embodiment each individual connecting means includes a pair of U-shaped members which cooperate with the same links. The legs 6 of one of these members project into the two links which the particular connecting means interconnects through one end of each of such two links, whereas the legs of the other member project into the two links through the other end of each of these two links. The base of each member is exterior of the two links and extends lengthwise of the bracelet.

The legs 6 of the members 4a and 4b cooperate with leaf springs 5 which are arranged within the links 2 and extend throughout the length of the latter and are transverse to the length of the bracelet. Each leaf spring is bent about a transverse spring axis so as to form an obtuse angle, the crest 5a engaging one side wall 3 and free arm portions 5b acting on the legs 6 of the U-shaped members 4 to urge the same toward the opposite side wall 3. The legs 6 are formed with transverse grooves 7 within which are received transverse projections 11 with which the spring 5 is formed at the free ends of its arms 5b. The grooves 7 and projections 11 thus form complementary projecting and receiving portions which serve not only securely to fasten the members 4 to the links 2, but also to mount these elements for pivotal

movement relative to each other so that the expansion bracelet is capable of assuming the contracted condition shown in Fig. 2 and an expanded condition such as is shown in Fig. 3 wherein the links 2 and members 4 together form a zig-zag configuration. Moreover, the arrangement of the parts is such that when the bracelet is expanded, the springs 5 are placed under stress, i. e., are flattened, and thus urge the bracelet back into its contracted condition. This may be achieved by making the width w of the legs 6 measured perpendicularly to the length of the bracelet greater than the height h of the legs between the leaf spring and the last-mentioned side wall of the link 2 measured perpendicularly to this width (Fig. 3).

In the above-described embodiment a separate spring 5 is provided for cooperation with opposite legs of the two U-shaped members 4 of the same connecting means. The links 2 may therefore be formed with transverse partitions 14 which extend substantially parallel to the plane common to the axis of the individual links 2. Each partition divides the interior of the respective link into two chambers, each of which is occupied by a spring 5 and the legs of the corresponding members 4. If desired, the partition 14 may be integral with the remainder of the link 2 and divide the interior thereof into two chambers of substantially the same size.

In the three embodiments shown in Figs. 4 to 7, 8 and 9 and 10 to 12, a single spring element is arranged within each of the links so that links incorporating one of the springs shown in these figures need not be provided with any partition. The single spring is substantially H-shaped and has a central web portion from which four arms emanate. The end portions of these arms cooperate, respectively, with the legs of both pairs of U-shaped members 4 which constitute the first and the second connecting means interconnecting to the adjacent links the particular link within which the H-shaped spring is located.

Thus, in the embodiment illustrated in Figs. 4 to 7, a spring 105 is arranged within a tubular link 102 having side walls 103, an upper wall 115 and a lower wall 116. The spring 105 is formed with elongated slots 108 so as to form the central web portion 109 the sides of which are pressed out as shown at 110. The free ends of the arms are formed with outwardly pressed projections 111 which are adapted to be received within corresponding grooves of the legs of the U-shaped members (not shown in Figs. 4-7). As is clearly shown in the figures, the spring is so formed that the arms on the same side of the slots 108 form an obtuse angle with each other and that the pressed-out portion 110 between the arms is pressed in a direction opposite to that in which the arms extend. Thus, the two portions 110 are pressed out in opposite directions and are so dimensioned that the distance a is substantially equal to the distance between the side walls 103 of the link 102 into which the spring is to be inserted, thus enabling the spring 105 to be snugly received within the link. Also, the arms and projections 11 are so formed that when the spring is actually inserted into a link, the spring is placed under at least some initial stress and that when the leg of a U-shaped connecting member is then inserted between the spring and the side wall of the link, the former is placed under still greater stress. It will be understood, therefore, that while it is very easy to insert a connecting member into a link containing a spring, or to remove such connecting member from such link, the connecting member will nevertheless be firmly retained by the spring and will cause the latter to be placed under still greater stress when the bracelet is expanded. The bracelet will thus automatically be returned into its contracted condition under the influence of the various springs.

In the embodiment shown in Figs. 8 and 9, the spring 205 having pressed-out portion 210 is formed with an additional cut-out 218 so that the four arms of the spring

are connected to each other by relatively small web portions 217. Otherwise, the spring 205 which is arranged within a tubular link 202 having side walls 203 and has projecting portions 211 received by transverse grooves 207 formed in the legs 207 of U-shaped members 204 is identical to the embodiment illustrated in Figs. 4 to 7.

In the embodiment shown in Figs. 10 to 12 the two spring halves of the spring 305 are parallel to each other and are interconnected by a central web 309 which is substantially perpendicular to both halves. A portion of each spring half is substantially flat and forms a surface 313 which is adapted to abut against the side wall of the link within which the spring is placed, the projecting portions 311 formed at the ends of the arms of the spring cooperating with suitable grooves formed in the legs of the U-shaped connecting members (not shown in Figs. 10-12).

In any of the above embodiments, the springs may instead of being in the form of a leaf spring be fashioned as wire springs, and the links and U-shaped connecting members may be made of any suitable material, as for example, metal, metal alloys, synthetic material, plastics, etc.

It will be understood that each of the elements described above, or two or more together, may also find a useful application in other types of expansion bracelet differing from the types described above.

While the invention has been illustrated and described as embodied in an expansion bracelet which is constantly urged toward and into its contracted condition, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. In an expansion bracelet in combination, a series of tubular links of substantially rectangular cross-section arranged in a single row extending lengthwise to the bracelet, each of said tubular links extending transversely to said row so that the bracelet has opposite engaging and outer surfaces lying in substantially parallel planes, each of said links having a pair of shorter opposite walls forming said outer and engaging surfaces, and a pair of longer opposite walls respectively located opposite corresponding longer walls of adjacent links; a plurality of first connecting means and a plurality of second connecting means, each of said connecting means being constituted by a pair of substantially U-shaped members having a base and a pair of legs, the legs of the U-shaped members of each pair projecting into two adjacent links from opposite ends of said links, said legs being arranged in two rows extending lengthwise to the bracelet and located respectively near said engaging and outer surfaces and entirely in opposite end portions of said links, and the bases of said U-shaped members being located outside of said links and extending in two rows lengthwise of the bracelet, the pairs of U-shaped members constituting said first connecting means being staggered lengthwise of the bracelet with respect to the pairs of U-shaped members constituting said second connecting means; and a pair of leaf springs resilient in longitudinal direction of the bracelet and located in each of said links and being respectively associated with said first and second connecting means, each spring of each pair of springs being engaged by a single pair of legs of a pair of said U-shaped

members and urging said tubular links into an abutting position in which said longer walls of adjacent links abut each other and in which the bracelet is contracted.

2. An expansion bracelet as set forth in claim 1 and including an element located in each of said links for holding the springs of the respective pair of springs spaced from each other for cooperation with said first and second connecting means, respectively.

3. An expansion bracelet as set forth in claim 2 where-
in said element is a partitioning wall in each of said links 10

located spaced equal distances from said outer and en-
gaging surfaces.

4. An expansion bracelet as set forth in claim 2 where-
in said element is a web connecting said springs of each
5 pair of springs.
